UNITED STATES PATENT OFFICE.

CHARLES O'HARA, OF LONDON, ENGLAND.

IMPROVED PROPELLER.

Specification forming part of Letters Patent No. 35,035, dated April 22, 1862.

To all whom it may concern:

Be it known that I, CHARLES O'HARA, of 4 Upper Seymour Street, West, London, in the United Kingdom of Great Britain and Ireland, have invented a new and Improved Propeller for Boats, Ships, and other Vessels; and I do hereby declare that the following is a full, clear, and exact description of the same, reference being had to the accompanying drawings, making part of this specification, in which—

Figure 1 is a stern view of a vessel having my propeller applied; Fig. 2, a central vertical section of the after part of the vessel and the propeller; Fig. 3, a plan corresponding with Fig. 2; Fig. 4, a horizontal section of the same, and Fig. 5 a perspective view showing the propeller in an inverted position.

Similar letters of reference indicate corresponding parts in the several figures.

This propeller is more especially adapted to the navigation of canals and other shallow waters, and therefore I have represented in the drawings its application to a flat-bottomed vessel suitable to that kind of navigation. It may be made of wood or iron; but I propose generally to make it of iron, and hollow; and it may be arranged with its axis either in a vertical position, as shown in the drawings, or in a horizontal position. I propose generally to arrange it in a semicircular recess, *a a*, Figs. 2 and 4, formed for its reception in the stern of the vessel; but two such propellers may be arranged, one on each side of the vessel.

The general form of the propeller is semi-cylindrical; but I prefer that the surface *b b*, which impinges upon the water, instead of being made a plane surface, should be corrugated parallel with the axis, as represented; and I also prefer in the vertically-arranged propeller to continue its upper horizontal surface, as shown at *c c*, to make it form a complete circle, such continuation consisting of a mere plate. The shaft *d* of this propeller, which is concentric with its arc-formed surface *e*, extends right through it, and the lower end of said shaft is fitted to a suitable bearing in a portion of the framing of the

vessel, and the upper portion thereof extends upward into the interior of the vessel for the connection of the engine by which the driving power is applied to the propeller, the manner of application of such power being such as to give the propeller an oscillating movement about its axis, and so cause each half of its impinging surface *b b* to strike the water alternately, the half on one side of the axis striking the water while the half on the other side returns to its initial or starting point, and the curved semicircular surface *e* preventing any reaction.

The method which I propose to adopt for applying the power is illustrated in Figs. 1, 2, and 3, and may be described as follows: The upper part of the shaft *d* has secured to it a toothed wheel, *l*, and has fitted loosely to it, above this wheel, an arm, *f*, to which is fitted and attached a slide, *g*, furnished with a tooth, *g'*, which works through a slot, *f'*, in the arm *f*, and which can be brought into any one of the spaces between the teeth of the wheel *e*, and so made to connect the arm with the shaft in such manner that by the connection of the piston-rod or connecting-rod of a reciprocating engine with the said arm the said arm may be made to work the propeller.

h is a lever working on a fixed fulcrum, *i*, and entering between two pins, *g² g³*, on the slide *g*, to work the said slide, and *j* is a notched post for the reception of the said lever to lock the slide and arm. By reversing the position of the arm *f* upon the propeller-shaft the impinging surface *b b* of the propeller may be turned in front, and the propeller so be made to back the vessel; or by shifting the said arm a less distance the propeller may be made to act sidewise upon the vessel to turn it in a very small circle.

When this kind of propeller is placed with its axis in a horizontal position, only the lower half should be submerged, and two propellers having their actions alternating with each other should be used.

What I claim as my invention, and desire to secure by Letters Patent, is—

1. The arrangement and operation of the semi-cylindric oscillating propeller within the concave *a a*, substantially as herein shown and described.

2. Having the radial face of the said propeller provided with corrugations *b*, as shown and described.

3. The combination, with the said propeller,

of the circular plate *c*, as herein shown and described.

CHARLES O'HARA.
